INTERCHANGEABLE STEEL FRAMEWORK
CONSTRUCTION

John G. Shodron, Fort Atkinson, Wis., assignor
to James Manufacturing Company, Fort Atkin-
son, Wis., a corporation of Wisconsin

Application January 22, 1935, Serial No. 2,899

2 Claims. (Cl. 189—1)

This invention relates to building structures and especially to that type of building structure wherein a metallic framework is fabricated at the mill in standardized interchangeable units and assembled at the building location.

An object of my invention is to provide a metallic building framework composed of interchangeable structural units which are of inexpensive yet efficient design, especially for buildings having large unobstructed floor space, such as farm buildings.

Another object is to provide such a framework, the units of which are grouped conveniently and braced efficiently in such a manner that the units are individually of extremely low weight so that they can be erected without the use of derricks or special hoisting apparatus, and yet of great structural strength when assembled in a building structure.

Another object is to provide such a framework wherein the horizontal stresses at the tops of the columns are transmitted to the foundation by an improved system of bracing.

Another object is to provide such a framework wherein the units are adapted for rectangular buildings to which round ends may be readily added.

Another object is to provide such a framework wherein the columns have offset overhanging portions permitting the use of shorter and, therefore, lighter truss sections.

Another object is to provide such a framework wherein the trusses are joined to the columns in a hinged connection through which the stresses are transmitted.

Another object is to provide an improved anchorage for securing the columns to the foundations.

In the drawings:

Figure 1 is a plan view of my improved building framework showing the end of a rectangular building with a rounded end portion joined thereto.

Figure 2 is an end elevation of the building shown in Figure 1, illustrating one method of bracing to transmit the horizontal stresses at the tops of the columns to the foundation.

Figure 3 is a modified form of bracing for the same purpose as Figure 2.

Figure 4 is another modified form of bracing for the same purpose as in Figure 2.

Figure 5 is an enlarged plan view of a girt or horizontal member connecting columns shown opposite the section lines 6—6 in Figure 1.

Figure 6 is an elevational view of the girt shown

in Figure 5, in the direction of the line 6—6 of Figure 1.

Figure 7 is an elevational section along the line 7—7 of Figure 1, showing the connections and bracing arrangements of a girt to a column.

Figure 8 is an enlarged plan view of a first-row strut shown opposite the section line 9—9 of Figure 1.

Figure 9 is an elevational view of the strut shown in Figure 8 in the direction of the line 9—9 of Figure 1.

Figure 10 is a section along the line 10—10 of Figure 11, showing details of connecting the bracing members to the struts and truss chords.

Figure 11 is an elevational section along the line 11—11 of Figure 1, showing the connections and bracing arrangements at the transition point between the straight and round sections of the building.

Figure 12 is an enlarged plan view of a second-row strut shown opposite the line 13—13 in Figure 1.

Figure 13 is an elevational view of the strut shown in Figure 12, in the direction of the line 13—13 of Figure 1.

Figure 14 is a sectional view along the line 14—14 of Figure 15, showing details of bracing arrangements in the second-row strut of Figure 12.

Figure 15 is an elevational section along the line 15—15 of Figure 1, showing the connecting arrangements of the second-row strut in Figure 12 at its point of connection with the struts in the round end of the structure.

Figure 16 is a plan view of the ridge strut and its connections in the center line of the building opposite the line 17—17 of Figure 1.

Figure 17 is an elevational view of the ridge strut shown in Figure 16, in the direction of the line 17—17 in Figure 1.

Figure 18 is an elevational cross section along the line 18—18 of Figure 1, showing details of the connections and bracing of the ridge strut of Figure 16, at its point of connection with the structural members of the rounded end of the building.

Figure 19 is an elevational cross section through the building in the plane of a pair of columns and the truss connecting them.

Figure 20 is a perspective view of an anchorage of a column to the foundation, for convenience showing the foundation as transparent.

Figure 49 is an elevation of a pair of the modi-

fied columns of Figure 40, supporting a truss hinged therebetween.

My terminology used herein is explained as follows:

A "bay" is a general area unit of the building plan between two adjacent columns and extending the full width of the building in a straight portion thereof, or to the center of the building in a rounded portion thereof. 5

A "panel" is a unit area, usually rectangular, of the structure between a pair of columns and a pair of girts, a pair of trusses and a pair of struts, or a pair of trusses with one girt and one strut. 10

A "bent" is a framework unit consisting of a set of columns, a pair of trusses, the struts and the laterals that form the frame over one bay of the building. 15

A "column" is a word having the usual meaning in the building art. 20

A "truss" is likewise a word having the usual meaning of the building art. 20

A "girt" is a horizontal built-up member spacing the columns apart and bracing them relative to each other. 25

A "strut" is a built-up member connecting spacing and bracing the roof trusses. 25

"Diagonals" refer to the tie rods that extend diagonally across the side wall panels from opposite ends of adjacent girts. 30

"Laterals" refer to the tie rods that extend diagonally across the upper and lower roof panels from opposite ends of adjacent struts. 30

In the following drawings and description, the trusses will be described by T-numerals, the columns by C-numerals, the girts by G-numerals, the struts by S-numerals, the diagonals by D-numerals and the laterals by L-numerals. 35

It will be understood that the building framework of my invention may be utilized for a rectangular building with rounded ends, or, if desired, these rounded ends may be omitted and a rectangular building is the result. The manner of bracing the columns in order to transmit the horizontal thrusts to the foundation will be as 40 equally applicable to a flat end as to a rounded end of a building framework. 45

General construction

In general (Figures 1 and 43), the building framework consists of a straight rectangular portion with unbraced bents, which terminates at each end in a bay containing a straight braced bent. Each such straight end bent contains all of the bracing rods as shown in the top portion of Figure 1, with the exception of the bracing rods shown in the central bent of each round end. The intermediate bents lack the cross bracing of the straight end bents. In a very long structure of this type, however, it might be necessary 50 to add a central bent which is cross-braced in the same manner as the straight end bents. With the design illustrated, however, only the end bents of the rectangular portion of the building are considered to be so braced. It will be noted that the cross-bracing rods in the central bent of the round end have been placed only in the outer panel: with my arrangement it has been found unnecessary to use such bracing rods in the inner panels thereof. These cross-bracing rods known as "laterals" will be required both in the upper and lower panels of the braced bent because of the depth of the roof trusses. In the side wall panels, however, only one set of the cross-bracing rods known as "diagonals" will be required 55 60 65 70 75

in each such section. It will be further noted that, while the outer struts S-1 extend entirely around the structure, the inner struts S-2 terminate with the braced end bents.

5   *Detailed structural arrangement*

Referring to the drawings in detail, Figure 1 shows the straight end bent of a rectangular building with a round end joined thereto. The 10 straight bent consists generally of girts G-1 on the extreme outer side walls of the bent joining vertical columns C-1 and C-2. Parallel with the girts G-1 are outer struts S-1 spaced inwardly from the girts G-1 and connected therewith by the laterals L-1 and L-2. Crossing the building between the columns C-1 is a truss T-1, while between the columns C-2 runs a 15 similar truss T-2. Spaced inwardly from the outer struts S-1 are struts S-3 parallel to the outer struts S-1 and connected with them by the laterals L-3 and L-4. Down the center of the building runs the ridge strut S-4, connected with the inner struts S-3 by the laterals L-5 and L-6.

20   The round end of the building is separated into bents by the columns C-2 and the girts G-2 connecting them. Running inwardly from the column C-2 to the end of the ridge strut S-4 are trusses T-3, T-4, T-5, and T-6.

25   Spaced inwardly from the girts G-2 and connecting the trusses T-2, T-3, T-4, T-5, and T-6 are the outer struts S-2. The panels bounded by the struts S-2, the girts G-2 and the trusses which they separate are free from the 30 bracing rods known as laterals except in the outer panel of the central bent, where the girt G-2 is connected to the outer strut S-2 by the laterals L-7 and L-8. The inner struts S-5 connecting the trusses T-2, T-3, T-4, T-5, and T-6 consist merely of a pair of rods without any secondary bracing, as it has been found that the convergence of the truss materially reduces the loads and span so that no cross-bracing or built-up construction is necessary for the 35 inner struts S-5. (Figure 43).

40   *Manner of bracing columns to transmit stresses to foundations*

In Figures 2, 3, and 4 are shown alternative 45 methods of bracing the columns by the cross braces known as "diagonals" in order to transmit the horizontal stresses from the tops of the columns to the foundations. These stresses naturally occur with greatest intensity where the 50 braced end bents of the building are located, since all the horizontal roof stresses are carried outward by this braced bent. In Figure 2 these stresses are transmitted into the side wall panels directly under this braced bent and carried by 55 the diagonals D-1 and D-2 and the girts G-2 and G-3. In the central upper panel, the diagonals D-1 connect the top of each column C-2 with the middle of the opposite column C-2, the 60 columns being centrally held together by the girt G-3. In the lower panel thereof the diagonals D-2 perform a similar function, and the girt G-4 ties the columns C-2 together near their 65 bottom ends. The girts G-4 are unnecessary for structural strength since their points of attachment are so near the points where the bases of the columns are attached to the foundation that the stresses are transmitted directly by the 70 columns to the foundation. They are useful, however, for spacing the bottoms of the columns

75   during erection, and for attaching the side walls and other structural members of the building.

The alternative arrangement shown in Figure 3 employs diagonals D-1 in the central upper panel and diagonals D-2 in the side wall panels connecting the girts and columns previously described. In this arrangement the stress is transmitted into the immediately adjacent side wall panel where it is carried by the girts G-2 and the diagonals D-1 to the girt G-3, by which it is communicated horizontally and transmitted through the lower panels on each side by the diagonals D-2. This arrangement frees the lower central panel for reception of doors or windows, and distributes the stress over a greater 10 area of wall. The second alternative arrangement of diagonals shown in Figure 4 is the preferred arrangement since it gives great strength and yet leaves the two central panels free for doors or windows. Here the stresses are transmitted horizontally through the girts G-2 into the side wall panels on either side of the braced roof bent and then carried downward into two bays of two panels each through the diagonals D-1 and D-2 and the girts G-2 and G-3.

The arrangements of diagonals in Figures 2, 3, and 4 have been described in connection with a building having a rounded end. Any one of these arrangements, however, can be utilized in a structure with straight ends by applying it to the first 15 straight bay where the diagonals extend into the first radial bay on one side and into a straight bay on the other. In addition it might also be applied to an intermediate straight braced bay where the side wall panels in adjacent bays are in the same 20 plane as those of the braced bay.

25   *Structural arrangement of girts and struts*

In Figures 5 and 6 are shown plan and elevational views of a girt G-1, the particular girt chosen being that viewed in the direction of the section lines 6-6 of Figure 1. This girt is a built-up member consisting of the outer chord 1, the inner chord 2, the cross members 3 joining the inner and outer chords, and the lattice members 4 which serve as oblique web braces for the girt. The lattice members 4 may consist of a continuous strip of material which is bent to an undulating form and welded at its crests 5 and troughs 6 to the chords 1 and 2, or else separate 30 strips may be used and welded at their opposite ends to their respective chords as shown in Figure 5.

The means of attaching the diagonals and girts to the column, as well as the first panel laterals, 35 is shown in Figures 5, 6, and 7. The columns C-1 and C-2 are provided with plates 7 drilled to receive two bolts 8 and 9. These bolts pass through the end connections 10 and 11 of girts G-1 and G-2 respectively. The bolt 9 carries 40 a clip angle 12, the outstanding part of which is positioned to receive the end of a diagonal such as D-1 or D-3. The end of such a diagonal is threaded to receive a nut 13 which secures the diagonal to the clip 12. Figure 7 shows the 45 arrangements of these parts, the projection of the lattice brace 4 having been omitted for the sake of clearness.

The trusses T-1, T-2, etc. terminate in flat 50 bars 14 which are punched to receive two bolts 15 and 16 which secure them to the extensions 17 of the columns C-1, C-2, etc. To the bolts 15 and 16 are secured clip angles 18 and 19 which 55 are punched to receive the threaded ends of 60

lateral L-1 and L-2 in the same manner previously described for the diagonals D-1. Figures 8, 9, 10, and 11 show the connections and construction of the outer struts at the location where the straight portion of the building joins the rounded portion. The trusses T-1, T-2, etc. have U-shaped clips 20 welded to their upper and lower chords 21 and 22, respectively. The struts S-1 and S-2 terminate in flat bars 23 and 24 which are punched to receive the bolts 25 which fasten them to the U-shaped clips 20. The bolts 25 also fasten an open U-shaped bar 27 to the clip 20. This clip bar 27 is punched to receive the laterals from adjacent panels on each of its outstanding legs. The upper clip bar 27 receives the laterals L-1 and L-3, whereas the lower one receives the laterals L-2 and L-4. Figure 10 shows the manner in which the flat bar 24 is welded to the chord of the strut S-2 on an angle so as to meet the clip 20, surface to surface. The lattice members 28 of the struts S-1 are welded to the upper and lower chords 29 and 30 thereof in the same manner as has been previously described for the girts G-1. The upper and lower chords 29 and 30 are also joined by the cross members 31.

Figures 12, 13, 14, and 15 show the inner strut S-3 and its related parts. The inner strut S-3 is similar in construction to the outer strut S-1, 30 and is fastened in the same manner. The strut consists of upper and lower members 32 and 33 connected by cross members 34 and by the lattice braces 35 welded to the chords. Similar U-shaped clips 20 are joined to the upper and lower chord members 21 and 22 of the trusses T-1, T-2, etc., and these on one side have secured to them the flat bar portions 36 in which the upper and lower strut members 32 and 33 terminate, as by the nuts 41.

As previously mentioned, the inner struts S-5 of the rounded portion of the building consist merely of the simple rods 37 and 38 without any lattice bracing or cross ties being necessary. Accordingly, in Figure 13 it will be seen how these upper and lower rods 37 and 38 are joined to the U-shaped clip 20 by being passed therethrough and held with nuts 40 on their threaded ends. Similar clip bars 27 are also held in place by the nuts 41, and through their legs pass the laterals L-3 and L-5 for the upper chord 32, and L-4 and L-6 for the lower chord 33.

Ridge strut construction

The ridge strut S-4 running along the center line of the building is heavier than the other struts since it carries the opposed forces of the opposite round ends of the building, these forces converging on the center line. The details of this ridge strut S-4, together with its connections to the radial trusses T-3, T-4, T-5, and T-6 and the transverse trusses T-1 and T-2 are shown in Figures 16, 17, and 18. Secured inside the top and bottom chords 21 and 22, respectively, of the trusses T-1 and T-2 are flat plates 42 and 43 arranged back to back and punched for four bolts 44, 45, 46, and 47, respectively. The ends 48 and 49 of the ridge strut S-4 abut face to face on the flat plates 42 and 43 respectively, and are held in engagement therewith by the two inner bolts 45 and 46, respectively. The two outer bolts 44 and 47 carry the upper clips 50 and the lower clips 51 through holes in which pass the threaded ends of the laterals L-5 and L-6, these laterals being held in place by the nuts 52.

The ends of the radially disposed trusses T-3,

T-4, T-5, and T-6 are connected with the ridge strut S-4 through semi-circular connector castings 53 and 54. The upper casting 53 contains radially disposed arms 55 which extend beneath the ends 56 of the top chords of the radial trusses T-3, T-4, T-5, and T-6 and also extend so as to connect casting 54 with the upper casting as shown by Figure 17, these ends 56 having holes 57 and 58 which match with corresponding holes in the connector casting 53, permitting bolts 59 and 60 to be inserted. The lower connector casting 54 resembles the upper one 53. In order to keep it from projecting below the ceiling line and yet avoid clamping on the flanges rather than on the web of the lower chords of the radial trusses T-3, T-4, T-5, and T-6, the lower chords 61 rest against the lower connector 54. A flat bar 62 is welded to the top side of the radial truss lower chords 61 and extends over the lower connector 54, a connection being made therethrough by the bolts 63. The lower connector casting 54 is bolted to the truss plate 43 in the same manner as the upper connector casting 53 is bolted to the plate 42.

Foundation and column anchorage

The manner of anchoring the columns to the foundation is shown in Figure 20. From the base plate 64 of the column, a long U-shaped anchor rod 65 extends downward into the foundation material which is generally of Portland cement. The upper ends of this rod 65 are threaded and engage the base plate 64 of the column by means of nuts 66. At an intermediate point along each arm of the anchor rod 65 are attached link members 67 and 68, meeting in a common connection 69 with a cross rod 70. The cross rod continues horizontally through the concrete for a considerable distance, as is better shown in Figure 19, terminating in an angled end 71 whereby it is given a greater holding power in the concrete. In this manner the column is securely anchored and the stresses coming from it are conveyed into the foundation.

Attachment of wall and roof coverings

The wall and roof coverings are not bolted directly to the metal columns, but are fastened to wooden nailing strips which are secured in the grooved portions of the metal frame members. Several arrangements for holding these nailing strips are shown in Figures 21 to 33 inclusive. It is to be understood, however, that the subject-matter of these nailing strips has been reserved to be claimed in a separate application for Letters Patent, and accordingly will not be claimed herein.

In Figure 21 is shown a cross section of a typical metal frame member 72 of a channel section type. Within the channel groove is fitted a wooden nailing strip 73. To secure this nailing strip within the channel, however, are provided retaining rods 75 which extend across the channel and are secured to either flange thereof by the welded connections 76, as will be better understood from Figures 22 and 23. The wood strip preferably extends partly above the level of the channel flanges, and in that case is grooved as at 77 to receive the retaining rods 75.

When it is desired to add the roof or wall coverings, these are readily nailed, either directly to the nailing strips 73, or else to purlins which are in turn nailed to the nailing strips 73. This construction results in a very strong frame member which is also exceedingly light in weight. The

lattice members of the trusses are also of light construction and are welded to the chord members thereof as has been previously described, resulting in a further reduction of weight. Consequently, the entire frame structure of the building may be assembled without the use of special derricks. An entire half truss extending from the column to the center of the building is so light that it may be picked up and carried by one man. The simplest tools and arrangements may thus be used in the erection of the structure, since the complicated portions thereof have been completely fabricated at the mill.

Figures 24 and 25 illustrate a frame structure having T-section chords 78, to which the nailing strips 73 are attached by means of the rivets 79 extending therethrough. The welded attachment of the lattice members 80 to the upper and lower chords of the truss is very clearly shown.

In Figure 26 is shown a structural member of a grooved cross section wherein the nailing strip is held within the groove by welded retaining rods in the manner previously described. In Figure 27 the groove of the chord member 81 is shown as of a U-section and, in Figure 28, of a channel section.

In Figures 29 and 30 is shown a frame structure having I-section chords 82. The nailing strips 73 are secured within one groove of the I-section by U-shaped retaining rods 83 (Figure 30), the ends of which are welded to the flanges of the chord member in the manner previously described.

In Figure 29, the lattice members 80 are shown as consisting of a continuous rod which is bent into an undulating form, the crests and troughs of which are welded to the chords in the manner shown. In Figures 24 and 26, the lattice members 80 were shown as consisting of separate pieces welded at their ends to the chord members.

In Figure 31 is shown a frame structure whose chords 84 are of angle section or L-section, a cross section of one connection being shown in Figure 32. The nailing strip 73 is secured between the flanges of the L-sections 84 by the use of retaining rods 75 welded thereto.

In Figure 33 is shown a cross section through a V-section chord member 85. The nailing strip 73 is of modified triangular section, and is held in the groove of the chord 85 by the usual welded retaining rods 75.

Column and truss construction

It will be obvious that various types of columns and trusses may be used in the construction of my improved structure. In Figures 34 to 41 are shown various types of columns suitable for this purpose.

Figures 34 to 36 illustrate ordinary types of columns. Figures 41 and 42 show a type of column which is especially suitable, and which is shown in use in Figure 19. This column consists of channel members 86 and 87 joined by cross members 88 and lattice members 89. The upper portion of the channel member 86 has an offset

direction so that its tip 90 overhangs the base of the column by a considerable amount. The base plate 64 of the column has already been described in connection with its anchorage to the foundation.

The columns shown in Figures 37 to 40 inclusive are of my overhanging construction. At the outermost upper tip 91 of each column consists of a hinge member to which the end of a truss member may be pivotally attached by means of a corresponding hinge portion.

In Figures 44 to 49 inclusive are shown various types of trusses and columns having my hinged connection 91 therebetween. Each of the columns has a hinge point 91 which considerably overhangs the base of the column, thus shortening the length of the truss and decreasing the weight thereof. This further facilitates the erection of the structure. Figures 44, 46, and 48 show the type of column of Figure 37 with various types of trusses. Figure 45 shows the Figure 38 column, Figure 47 the Figure 39 column, and Figure 49 the Figure 40 column, each with a particular form of truss hinged to it. The dotted lines 92 in Figures 44 to 49 inclusive denote "nominal members", that is, members which are added merely for the attachment of roof coverings, but which are unnecessary as far as the structural soundness of the building is concerned.

As previously stated, the building framework has trusses T-1 and T-2 at each end of the straight portion of the building, these trusses being strongly cross braced, as shown in Figures 1 and 43. The trusses T-3, T-4, T-5, and T-6 within each curved end of the building are partially braced. The other trusses T in the straight portion of the building between the trusses T-1 lack this cross bracing, being connected merely by the girts G-1, the outer struts S-2 and the ridge struts S-4. Each truss has upper chords 21, lower chords 22, cross-members 93 and lattice members 94.

It will be understood that I desire to comprehend within my invention such modifications as may be necessary to adapt it to varying conditions and uses.

Having thus fully described my invention, what I claim as new and desire to secure by Letters Patent is:

1. In a building structure, a truss having upper and lower chords, and supporting members attached to the midpoint of said upper and lower chords for the support of trusses arranged radially outward therefrom, and means connecting said supporting members.

2. In a building structure, a truss having upper and lower chords, and supporting members attached to the midpoint of said upper and lower chords for the support of trusses arranged radially outwardly therefrom, means connecting said supporting members, and at least one of said supporting members having radially disposed arms attached thereto.

JOHN G. SHODRON.
